US0D1022842S

(12) **United States Design Patent** (10) Patent No.: **US D1,022,842 S**
(45) Date of Patent: ** Apr. 16, 2024

(54) **WATER BIKE**

(71) Applicant: **Ranzhi (Weihai) Outdoor Products Co., Ltd.**, Weihai (CN)
(72) Inventor: **Yuan Gao**, Shandong (CN)
(***) Term: **15 Years**
(21) Appl. No.: **35/517,038**

(22) Filed: **Apr. 5, 2023**

(80) **Hague Agreement Data**

Int. Filing Date: **Apr. 5, 2023**
Int. Reg. No.: **DM/228411**
Int. Reg. Date: **Apr. 5, 2023**
Int. Reg. Pub. Date: **May 5, 2023**

(51) **LOC (14) Cl.** **12-06**

(52) **U.S. Cl.**

USPC **D12/306**

(58) **Field of Classification Search**
